(57) **CLAIM**

The ornamental design for a pistol, as shown and described.

DESCRIPTION

FIG. 1 is a left side view of a pistol according to a first preferred embodiment of the new design;

FIG. 2 is a right side view thereof;

FIG. 3 is a front view thereof;

FIG. 4 is a rear view thereof;

FIG. 5 is a top view thereof;

FIG. 6 is a bottom view thereof;

FIG. 7 is a perspective view thereof;

FIG. 8 is a left side view of a pistol according to a second preferred embodiment of the new design; the front, rear, top, and bottom views of the second preferred embodiment are the same as those corresponding views in the first preferred embodiment; and,

FIG. 9 is a right side view thereof.

All broken lines shown in the drawings are for illustrative purposes only and form no part of the claimed design.
